DESIGN FOR A MICROTOME

Gustave Fassin, Irondequoit, N. Y., assignor to
Bausch & Lomb Optical Company, Rochester,
N. Y., a corporation of New York

Application April 26, 1935, Serial No. 56,591

Term of patent 14 years

To all whom it may concern:

Be it known that I, Gustave Fassin, a subject of the King of Belgium and a resident of the town of Irondequoit, county of Monroe, and State of New York, have invented a new, original, and ornamental Design for Microtome, of which the following is a specification, reference being had to the accompanying drawing, forming a part hereof.

The figure is a perspective view of a microtome, showing my new design.

The side of the housing, not shown in the drawing, is of the same contour as the side shown except that the front edge is vertically straight rather than curved.

I claim:

The ornamental design for a microtome, as shown and described.

GUSTAVE FASSIN.
